SLICING AND STORING DEVICE

James W. Jacobs, Dayton, Ohio, assignor to General Motors Corporation, Detroit, Mich., a corporation of Delaware

Application October 21, 1952, Serial No. 316,027

5 Claims. (Cl. 31—22)

This invention relates to an article of manufacture and particularly to a storing and slicing device for butter or the like.

A general object of my invention is to provide an inexpensive lightweight portable combined butter storing and slicing device adapted to be placed in the food storage compartment of a refrigerator cabinet for preserving the butter and removable therefrom to be placed on a table top for operation in dispensing small pats of butter therefrom.

Another object of my invention is to provide an improved device capable of receiving, storing and slicing pats from different dimensioned one-quarter pound elongated prints, bars or sticks of butter or the like whereby the device is rendered universal in use throughout various localities of the country.

Another object of my invention is to provide a combined butter or the like storage and slicing device with improved indexing means for shifting a bar of butter therein along its support and past a cutting means on the device during successive operations thereof for severing and dispensing parts therefrom.

A further object of my invention is to provide a combined storing and slicing device with a cover member slidably in a straight line direction relative to another member of the device supporting a bar of butter or the like to render a cutting means in the device effective for severing flat sided pats from the butter bar.

A still further and more specific object of my invention is to provide a portable butter storing and slicing device comprising two members connected together for reciprocating sliding movement in a straight line direction with means for successively indexing a portion of the butter past a cutting means on the device and to render the indexing means and the cutting means effective during the same or down stroke of reciprocating movement of one of the members relative to the other.

With the foregoing and other objects in view, my invention resides in certain novel features to be herein-after more particularly pointed out in the specification and illustrated in the accompanying drawings and, while this disclosure depicts my present preferred form of device, changes in construction and arrangement of parts can be made without departing from the spirit of the invention as set forth in the appended claims.

In the drawings:

Figure 1 is a perspective view of a portable butter storing and slicing device constructed in accordance with my invention;

Figure 2 is an enlarged vertical sectional view taken on the line 2—2 of Figure 1 showing the device in normal closed position with a bar of butter therein;

Figure 3 is a view similar to Figure 2 showing the cover or hood of the device raised upwardly of the supporting base thereof in a position of initial down stroke movement to index the bar of butter forwardly of the device past its cutting means;

Figure 4 is a view similar to Figure 3 showing the

2

indexing means in the device in a position ready to move and cut the last pat from the butter bar;

Figure 5 is an enlarged fragmentary broken sectional view taken on the line 5—5 of Figure 2 showing the hinged mounting of the door to the device and illustrating details of the cutting means;

Figure 6 is a vertical sectional view through the device taken on the line 6—6 of Figure 2 showing a butter bar backing block associated with the indexing means of the device to connect the cover member to the supporting base thereof;

Figure 7 is a horizontal sectional view of the device taken on the line 7—7 of Figure 6 showing means for guiding the movement of the cover relative to the supporting base;

Figure 8 is a horizontal fragmentary sectional view taken on the line 8—8 of Figure 6 showing a cut back portion of the top wall of the supporting base and showing finger grip notches in the indexing block; and

Figure 9 is a fragmentary vertical sectional view showing the indexing block in a position to be removed from the device to permit separation of the cover thereof from its supporting base member.

In the present illustration of this invention I have shown in Figure 1 of the drawings an article of manufacture in the form of a combined portable butter storage and slicing device. The device is of rectangular form and when butter is placed therein it is intended to be stored in a refrigerated food compartment of a refrigerator cabinet maintained at, say for example, 40° to 45° F. Such temperature has been found capable of preserving butter over a long period of time. The device includes a first inner support or base member 11 comprising a housing having an open end. Member 11 has a horizontal elongated compartment 12 in its lower portion which receives and removably supports a shallow tray 14 (see Figures 2 and 6). The top wall 16 of compartment 12 forms a ledge or platform for the reception of a one-quarter pound print or bar of butter indicated by the dot-dash lines 17 in Figures 2, 3 and 4 of the drawings. While my device is primarily intended for storing and slicing butter into pats it is to be understood that any preformed edible substance or units may be placed therein. The support member 11 includes thickened lower side and rear wall portions which are hollowed out as at 13 for receiving lower leg-like portions 15 (see Figure 6) of walls of a cover or hood member to be presently described. The upper portion of the side and rear walls of support member 11 extend above the platform 16, as at 18, and each of these side walls has a thin integral longitudinal projection 19 (see Figures 2 and 6) extending inwardly thereof over the front portion of platform 16 for a purpose to be hereinafter described. Each side wall 18 also has an integral inwardly directed boss 21 (see Figure 6) formed thereon and being coextensive with the platform 16 (see Figure 2) to provide a guide for a follower block 22 disposed in back of the bar of butter 17 on platform 16 for a purpose to be herein-after more fully described. The longitudinally extending bosses 21 also serve to space the bar of butter 17 from walls 18 to reduce friction therebetween when the slicing device is manipulated. Follower block 22 has four cutout portions 24 two of which receive the opposed projections 19. By providing the follower block 22 with the four cutout portions 24, each opposed pair of which are spaced a like distance from the top and bottom respectively of block 22, it makes no difference whether the block is placed into the device right side up or upside down. In either event there will be a pair of the cutout portions 24 aligned with and ready to receive the opposed projections 19 when the block 22 is pushed

into the device from the open end of supporting housing or member 11. The block 22 is also provided with four finger grip depressions 25 utilized for a purpose to be hereinafter described. A pin or rod 26 passing through block 22 has its ends projecting through the walls 18 in a cutout slot 27 provided therein (see Figure 6) and extending from the open front edge of member 11 back to a point adjacent the rear end thereof (see Figure 2). The ends of pin or rod 26 project outwardly a substantial distance from the walls 18 for a purpose to be hereinafter described. Support or housing member 11 is provided with a set of vertical side rails 31 adjacent the front thereof and a set of vertical end rails 32 at the rear thereof (see Figure 7). Both sets of rails 31 and 32 are in the form of straight integral bosses extending outwardly from member 11. 15

The present device also includes a second member, hood or cover 36 which encloses the bar or print of butter 17 and portions of the base or support member 11. This cover member 36 has an opening in its front end and is open at its bottom so as to straddle the walls 16 and 18 of support member 11. The front and rear leg-like portions 15 of member 36 fit and are slideable in the hollowed out portions 13 of base or support member 11. Cover member 36 is provided with vertical slots 37 in each of its side walls and a pair of similar slots 38 in its rear wall to receive the rails 31 and 32 respectively (see Figure 7). Thus the sets of rails 31 and 32 on support member 11 and the sets of slots 37 and 38 on the cover or hood member 36 form complementary guide means for slidably connecting these members together. The guide means is straight to permit cover member 36 to be bodily reciprocated in a straight line perpendicular direction with respect to the extension of the butter supporting platform 16 and the length of support member 11. Cover member 36 carries a cutting means adjacent the opening in the front thereof. This cutting means is in the form of a wire 41 extending horizontally across the front of member 36 in a normal position slightly below the butter supporting surface of the platform or top wall 16 of tray compartment 12 (see Figures 2 and 5). One end 42 of wire 41 is soldered or otherwise stationarily secured to a set or the like screw 43 threaded into a hole provided in the one side wall of cover member 36 (see Figure 5). The other or free end 44 of wire 41 has a ball 46 rigidly secured thereto and rotatably riding in a socket portion of a plug 47 located in a counter-bored hole in the other side wall of cover member 36 (see Figure 5). The tension of the cutting wire 41 may be adjusted by turning set screw 43 within the tapped hole as is desired or necessary. 40

The inner surface of each side wall of cover member 36 is cut or notched out to provide an indexing arrangement or means for the device. This indexing means is of such character as to be rendered effective by straight line sliding or reciprocating movement of cover member 36 relative to the support member 11. The cut or notched-out portions in the inner surface of each of the vertical side walls of cover member 36, facing member 11, include a longitudinal groove 49, terminating in spaced relation to the front and back of member 36 (see Figures 3 and 4) and a plurality of equally spaced apart vertically disposed matching grooves 50 communicating with one another at a point spaced from their lower ends and having their upper ends communicating with or opening into the horizontal groove 49. The lower portion of the opposed sets of vertical grooves 50 are provided with offset portions, indicated at 51, directed toward the rear of the device (see Figure 2). The side walls of the opposed sets of grooves 50 are shaped to provide camming surfaces as indicated at 52, 53 and 54 for the purpose of directing pin or rod 26 along the indexing means as will be explained. The projecting ends of pin or rod 26 pass through the slots 27 and extend into the grooves of the indexing means 75

for the purpose of shifting the follower block 22 and consequently a bar of butter placed in the device and supported on platform 16 in a manner to be presently described. The projection of pin or rod 26 into the grooves of the indexing means also serves as means for connecting the members 11 and 36 together. Each side wall of member 36 is also cut out or notched as at 55 to provide a horizontal groove extending from the bottom of the frontmost set of grooves 50 to the front edge portion of member 36. The grooves 55 in member 36 form passageways adapted to coincide with the opposed slots 27 in member 11 when cover member 36 is at the top of its upstroke for a purpose to be hereinafter described. 5

A door 56, hinged to support member 11, by pins or the like 57, closes the open front end of the device and has a hooked top tongue portion 58 snapped over a lip 59 provided at the front edge of the top wall of cover member 36. The closed position of door 56 normally prevents movement of the cover member 36 relative to the support member 11. When door 56 is opened its inner surface is disposed substantially on the same horizontal plane with the top surface of the bottom wall of compartment 12 which supports the tray 14 and therefore when tray 14 is moved outwardly of compartment 12 it is partially supported by this opened door (see Figures 3 and 4). 20

The chamber or space between walls 18 above platform 16 of member 11 is of such size as to receive bars of butter which may vary somewhat in dimensions so that the present device is rendered universal in use. For example, there are two different sized one-quarter pound bars of butter retailed throughout this country for consumption in homes. There is one normally referred to as a "West Coast" standard size print or bar which is 1½" wide, 1½" high and 3¾" long. There is another usually referred to as an "East Coast" standard size print, bar or stick which is 1¼" wide, 1¼" high and 45/8" long. The present device is designed to receive and cut pats from either one of these differently dimensioned bars of butter. The dot-dash line showing of the bar of butter 17 in the drawings represents the standard "East Coast" size and when a standard "West Coast" size bar of butter is placed in the device the thin projections 19 extending inwardly of the walls 18 bite a greater distance into the bar. 30

45 Since it is desirable that the user of the present device may view its contents, to determine the amount therein, I prefer to construct the device or at least portions thereof of clear plastic material. Thus support member 11 and cover member 36 and/or door 56 or all three of these elements are preferably fabricated from a transparent thermoplastic acrylic (methyl methacrylate) resin material. This enables the butter contained in the device to be seen from exteriorly thereof and the operator can readily ascertain the supply stored therein. 50

55 In preparing the present device for use, the door 56 is opened and an unwrapped one-quarter pound print, bar or stick of butter is placed on the front edge of platform 16 and pushed into the support member 11. The projections 19 bite into the bar of butter 17 to retain it in a flat position so as to prevent tilting thereof during slicing operations. If the block 22 is at the front of the device the bar of butter will abut and move the same to the rear thereof. It being understood that pin 26 in block 22 freely moves horizontally in the opposed matching longitudinal grooves 49 of the indexing means to a point above one of the rearmost vertical sets of grooves 50 (see Figure 2). After loading the device as described, its front door 56 may be closed, to substantially seal the butter therein (see Figure 1), and the loaded device is placed in a refrigerator cabinet for preserving the butter at a low temperature of from 40° to 45° F. Shortly prior to mealtime the device may be removed from the refrigerator and placed on top of a table or work ledge for operation to slice the desired number of pats from the bar of butter 17 60

therein. While base or support member 11 rests on the work ledge the front door 56 of the device is opened to thereby unlock the cover member 36 from support member 11. Cover member 36 is then manually elevated relative to member 11. The fully elevated position of member 36 relative to member 11 is shown in Figure 9 of the drawings. The base part of member 11, which has the hollowed out portions 13 receiving the leg-like portions 15 of member 36, serves as means for grasping the device with one hand while raising the cover member 36 with the other hand. The complementary guide means, formed by the sets of rails 31, 32 and slots 37, 38 causes the up and down reciprocating movement of cover member 36 relative to support member 11 to be in a straight line direction. Pin or rod 26 is normally positioned in the horizontal groove 49 of the indexing means above one opposed set of vertical grooves 50 at the rear of the rows thereof (see Figure 2). The initial upward movement of cover member 36 causes the ends of pin or rod 26, in block 22, to enter one of the rear sets of opposed vertical grooves 50 of the indexing means. Continued upward movement of cover member 36 causes the pin or rod 26 to ride or slide downwardly in these grooves whereupon it engages the cams 52 and moves around the curved offset portion 51 thereof into engagement with the cam surfaces 53 which direct the same into the bottom end of the grooves 50 to thereby terminate the upstroke movement of member 36. This may momentarily move the follower block 22 back away from the end of the bar of butter 17 without any beneficial or detrimental result. It is to be understood that block 22 and its pin or rod 26 can move only in a direction longitudinally of the slicing device and that other movement of pin or rod 26 herein referred to in describing the function of the indexing means is actually the sliding movement of the slots or side wall portions thereof relative to pin or rod 26.

Having completed the upstroke of cover member 36, as shown in Figure 9 of the drawings, it may now be manually slid downwardly relative to support member 11. As cover member or hood 36 is initially slid in a downward direction relative to base or support member 11 the pin or rod 26 leaves the bottom of the opposed rear grooves 50 and is caused to engage the camming surfaces 54 (see Figures 3 and 4) of the next forward set of opposed vertical grooves 50. Further downward movement of member 36 causes the camming surfaces 54 to force the pin or rod 26 and block 22 forwardly of the device toward its open front end a distance equal to the distance of horizontal spacing of the vertical grooves 50. This sliding movement of block 22 consequently shifts the bar of butter 17 forwardly along its supporting platform 16 so that a portion thereof moves past the cutting means or wire 41. It being understood that wire 41 is still elevated above the bar of butter 17 when a portion of the forward end of the bar is moved horizontally past the wire cutter 41 by the indexing means upon initiating the downward stroke of member 36. Continued downwardly sliding movement of cover member 36 relative to support member 11, after a portion of the bar of butter 17 has been moved past wire 41 by the indexing means, forces the cutting wire 41 through the butter and slightly below the front edge of platform 16 to thereby sever a flat sided pat from the butter bar. When cover member 36 reaches the end of its downstroke of reciprocation the pin or rod 26 is again located in the opposed horizontal grooves 50 of the indexing means or arrangement above and in vertical alignment with the grooves 50 through which it has just passed in rendering the indexing means effective. Thus on the next succeeding reciprocating movement of cover member 36 relative to support member 11 pin or rod 26 will ride or slide downwardly through these same grooves 50 so as to be cammed over, by the camming surfaces 52, 53 and 54 respectively, to the next forward set of grooves 50 for again indexing the bar of butter 17 toward the front of the device to push a portion

thereof beyond the cutting wire 41. It will be noted that indexing of the butter bar 17 forwardly toward the open end of the device and the cutting operation are both carried out during the downstroke of reciprocating the cover member 36 relative to support member 11. This permits cover member 36 to be elevated relative to base member 11 with a minimum of force to thereby reduce likelihood of the device being raised off its table top support during manipulations thereof. The tongue and groove guide means, rails 31 and 32 and slots 37 and 38, cause the reciprocating movement of cover member 36 to be in a straight line direction relative to the support or base member 11. This straight line direction of reciprocating movement of the members 11 and 36 relative to one another is advantageous in that the cutting wire 41 passes in a straight line through the bar of butter 17 and severs uniform flat sided pats therefrom instead of pats having curved or convexed and concaved sides. Successive reciprocating movements of cover member 36 will permit the severing of as many pats from the bar of butter 17 as are desired. In Figure 3 of the drawings I show the device as having been operated a few times to move the block 22 away from the rear portion thereof and in Figure 4 the device is in a position ready to index the block into its forwardmost point of movement by the indexing means to remove the last pat of butter from the bar 17 thereof. After any desired number of butter pats have been dispensed from the device, door 56 is closed, to again substantially seal the butter in the device, and the device is replaced in the food storage compartment of the refrigerator cabinet for preservation. Due to the plastic mass of the device it maintains butter therein at a low temperature for a substantial period of time which is ample to permit prolonged slicing operations without materially increasing the temperature of the butter while the device is out of the refrigerator.

The tray 14 within compartment 12 may be pulled outwardly of this compartment so as to rest on door 56 beneath the wire 41 while cutting and dispensing pats of butter from the bar 17 (see Figures 3 and 4). The dispensed pats will be received in tray 14 and this tray may be removed from the device and utilized for serving the butter pats at the dinner table. It being understood that the cut pats exposed to room temperatures will soon attain a desirable spreading temperature of, say for example, from 60° to 65° F. The tray together with any pats of butter left therein, after finishing a meal, may be reinserted into compartment 12 of the device by opening the refrigerator cabinet door and the door 56 of the device. If tray 14 is not used as a serving tray in the manner described it may be employed for receiving a one-quarter pound print, bar or stick of butter in compartment 12 which can be stored in the device within the refrigerator cabinet along with the butter bar 17 supported on the platform 16.

Since pin or rod 26 normally locks cover member 36 against detachment from the base or support member 11 it is desired to set forth the manner in which these members may be separated in order to facilitate the cleaning of chips or fragments of butter from the interior of member 11. After the last pat of butter has been cut from the bar 17 thereof, upon the final downstroke of cover member 36 relative to member 11, the pin or rod 26 will be disposed in grooves 49 at the top of the vertical opposed grooves 50 closest to the open front end of the slicing device. If the interior of member 11 is now to be wiped or washed out, prior to inserting another bar of butter into the device, cover member 36 is elevated relative to base member 11 to cause the pin or rod 26 to be located in the bottom of the forwardmost opposed grooves 50 in horizontal alignment with the cutout passageways 55. At this time the passageways 55 coincide or are in horizontal alignment with the opposed cutout slots 27 in walls 18 of support member 11 (see Figure 9). The finger grip depression 25 in the top of block 22 may be grasped

by the operator's finger to thus pull the block forwardly out of the open front end of the device. The front edge of the top wall of support member 11 is cut back as at 29 (see Figure 8) to permit the operator's finger to reach the finger grip depression in block 22. It being understood that during this outward movement of block 22 the ends of pin or rod 26 slide along the aligned passageways 55 and cutout slots 27. After removing block 22 from the device cover member 36 can then be freely removed upwardly away from base or support member 11 to permit this latter member to be thoroughly cleaned.

From the foregoing it should be apparent that I have provided an improved butter storage and slicing device wherein movable parts thereof are slidably reciprocated relative to one another in a straight line direction perpendicular to the bar of butter therein to sever flat sided pats from the bar as compared to a device which cuts the pats with curved sides. My improved device when closed and stored in the refrigerated food storage compartment of a refrigerator cabinet substantially seals the butter therein and prevents the same from absorbing odors from other and particularly odoriferous foods in the refrigerator. By providing my improved device with a removable serving tray and positioning the same in a compartment therein, capable of receiving a bar of butter in addition to the one to be cut into pats, I increase the utility and advantages of such a device. The present device is small and compact, simple in construction, is portable and is readily operable by housewives.

While for form of embodiment of the invention as herein disclosed constitutes a preferred form, it is to be understood that other forms might be adopted, as may come within the scope of the claims which follow.

What is claimed is as follows:

1. A combined storing and slicing device comprising, a support member having a horizontally elongated platform for receiving a bar of butter or the like and provided with opposed side walls extending upwardly thereabove, said side walls each having a longitudinally extending lateral inwardly directed projection adapted to bite into the bar, an elongated cover member separate from and movably connected to said support member, said cover member forming a hood over the bar, said platform and its side walls, cutting means fixed to said hood, said support member and said hood being provided with complementary guide means adjacent each end thereof, said hood being slidable along said opposed guide means relative to said platform on said support member in a direction perpendicular to the disposition thereof, the sliding movement of said hood forcing said cutting means through the bar to sever a pat therefrom, and said projections on the side walls of said platform preventing tilting of the bar within said device while forcing said cutting means through the bar.

2. A combined storing and slicing device comprising, a support member having a horizontally elongated platform for receiving a bar of butter or the like and provided with opposed side walls extending upwardly thereabove, said side walls each having a longitudinally extending lateral inwardly directed projection adapted to bite into the bar, an elongated cover member separate from and movably connected to said support member, said cover member forming a hood over the bar, said platform and its side walls, cutting means fixed to said hood, said sup-

port member and said hood being provided with complementary guide means adjacent each end thereof, said hood being slidable along said opposed guide means relative to said platform on said support member in a direction perpendicular to the disposition thereof, the sliding movement of said hood forcing said cutting means through the bar to sever a pat therefrom, said projections on the side walls of said platform preventing tilting of the bar within said device while forcing said cutting means through the bar, and means pivotally mounted on said support member and latched to said hood for locking said hood against movement relative to said support member.

3. A combined storing and slicing device comprising, a support member having a horizontally elongated platform for receiving a bar of butter or the like and provided with opposed upstanding side walls, said walls having sets of spaced apart vertical guide means thereon adjacent opposite ends of said support member, a horizontally elongated cover member separate from and movably connected to said support member by spaced apart sets of guide means at opposite ends thereof complementary to said sets of guide means on the upstanding side walls of said support member, said separate cover member forming a hood over portions of the side walls of said support member and concealing the bar on said platform, cutting means fixed to said hood, said hood being slidable along said sets of guide means relative to said platform in a straight line direction perpendicular to the disposition thereof, said spaced apart sets of guide means at the ends of said horizontally elongated device cooperating with one another to prevent binding of said hood during sliding thereof, and the sliding movement of said hood forcing said cutting means through the bar to sever a pat therefrom.

4. A device as defined by claim 3 wherein the cover member is detachable from the support member to provide access to the interior of the device for cleaning same.

5. A combined storing and slicing device comprising, a support member having a horizontally elongated platform for receiving and supporting a bar of butter or the like, said support member being provided with side walls extending upwardly from said platform, said side walls each having a longitudinally extending inwardly directed projection adapted to bite into the bar, an elongated cover member separate from and movably connected to said support member, cutting means fixed to said cover member, said support member and said cover member being provided with complementary guide means, said cover member being slidable along said guide means relative to said platform on said support member in a straight line substantially perpendicular direction to the horizontal extension thereof, the sliding movement of said cover member forcing said cutting means through the bar to sever a pat therefrom, and said projections on the side walls of said support member preventing tilting of the bar on said platform during the act of forcing said cutting means through the bar.
